UNITED STATES PATENT OFFICE.

CHARLES D. BLINN, OF PORT HURON, MICHIGAN.

IMPROVEMENT IN FLEXIBLE HARROWS.

Specification forming part of Letters Patent No. 77,574, dated May 5, 1868.

To all whom it may concern:

Be it known that I, CHARLES D. BLINN, of Port Huron, in the county of St. Clair and State of Michigan, have invented a new and useful Improvement in Flexible Harrows; and I do declare that the following is a true and accurate description thereof, reference being had to the accompanying drawing, and to the letters of reference marked thereon, and being a part of this specification.

The object of this invention is to construct a cheap and economical harrow which will be so flexible as to operate upon uneven ground and easily clear obstructions, and at the same time do its work thoroughly and well.

In order to accomplish this end, I use the parallel bars A, as many or as few as the nature of the work, the state of the ground, and the power applied may demand. Into these parallel bars I insert the ordinary iron or steel harrow-teeth, in the usual way, and connect the bars by the links C and the solid link D. The links C are double and act as hinges, to allow for the play of the bars in passing over uneven ground. The links pass around the bars, one end inside the end tooth of one bar and the other end outside the end tooth of the next bar. The draft, being at the clevis E and from near the corner of the harrow, produces a diagonal direction of the harrow when in use, which diagonal direction, with the position of the links, will prevent the links from slipping off by the draft being directly against the outer teeth, thereby securing the whole

together while in use. By this arrangement of the links they admit of the bars being easily taken apart for transportation or storage. The solid link D is rigidly fastened to the bars which it connects together, to prevent any undue tilting of the rear bar in the harrow.

The flexibility given by the connecting-links, as above described, will allow the harrow to pass obstructions without elevating the whole apparatus, and should the obstructions be met with at the ends of either of the bars, the same will yield laterally in its passage independently of either of the other bars, and not disarrange the whole, as would be the case were the whole of the bars rigidly attached together.

The bars, links, and teeth being all alike admits of the removal or addition of as many or as few bars as may be desirable to accomplish the work desired, and greatly facilitates repairs when necessary.

What I claim as my invention, and desire to secure by Letters Patent, is—

1. The double links C, when operated in connection with the bars A in the position herein described.
2. The solid link D, in connection with the above-mentioned parts when constructed and operating substantially as and for the purposes herein set forth.

CHARLES D. BLINN.
